UNITED STATES PATENT OFFICE.

ANTON JULIUS SKJENNEBERG, OF EMBRETSFOS, MODUM, NORWAY.

METHOD FOR REMOVING THE PULP FROM CONTINUOUSLY-MOVING SCREENS.

1,263,476.

Specification of Letters Patent. Patented Apr. 23, 1918.

Application filed November 10, 1917. Serial No. 201,284.

To all whom it may concern:

Be it known that I, ANTON JULIUS SKJENNEBERG, a subject of the King of Norway, residing at Embretsfos, Modum, in the 5 Kingdom of Norway, have invented certain new and useful Improvements in Methods for Removing the Pulp from Continuously-Moving Screens; and I do hereby declare the following to be a full, clear, and exact 10 description of the invention, such as will enable others skilled in the art to which it appertains to make and use the same, reference being had to the accompanying drawings, and to letters or figures of reference 15 marked thereon, which form a part of this specification.

The present invention has for its object a method for removing the pulp from continuously moving screens and the principal feature of the invention consists in placing a bar or cylinder of pulp between the screening surface and a stationary surface forming an angle with the screening surface.

The said pulp bar or cylinder will be rotated by its contact with the surface of the screening cylinder and during this rotation will continuously remove the pulp from the outside of the screening cylinder the pulp adhering more firmly to the pulp cylinder 30 than to the screening surface.

At a certain distance from the said cylinder is placed a stationary scraper or the like which comes into contact with the pulp cylinder when the same has reached a certain 35 diameter. From this moment the said scraper will remove all pulp adhering to the surface on the pulp cylinder maintaining the same on a certain diameter. The said scraper may conveniently be formed by the 40 upper edge of the stationary surface supporting the pulp cylinder.

The method is particularly adapted for rotating screening cylinders and is applied to the same by mounting a sloping board at 45 some little distance from the upwardly moving part of the screening cylinder in such a manner that a wedge shaped channel is formed between said board and the screening surface. A ball of pulp is placed in 50 the said channel and this ball rapidly grows in the manner of a snow-ball finally forming a bar or cylinder filling the channel along the whole length of the screening cyl-

inder. When the diameter of this pulp cylinder has reached a certain size the cylinder 55 will continuously scrape against the upper edge of the board thus removing pulp from the cylinder and parting with it over the edge of the board.

In the accompanying drawing is illustrated 60 an arrangement by means of which the method may be carried out.

1 indicates part of the screening surface of a rotating screening cylinder which moves in the direction indicated by the arrow. 65

2 is a board which extends along the screening surface without touching the same and the upper end surface 3 of which forms a wedge shaped channel 4 with the screening surface. The pulp cylinder formed in this 70 channel is illustrated on the drawing with the diameter it finally attains all new pulp taken up by the cylinder 5 being then scraped off by means of edge 6 of board 2.

Claims: 75

1. The method of removing pulp from a moving screen or the like, which comprises supporting a body of pulp in floating contact with the surface of the screen, whereby the pulp on the screening surface will adhere to said body and be removed from the screen.

2. The method of removing pulp from a continuously moving screen or the like, which comprises supporting a body of pulp 85 between an upwardly moving part of the screening surface and a stationary surface so as to permit the rotation of said body, whereby the pulp on the screening surface will adhere to the rotating body and be removed from the screen.

3. The method of removing pulp from continuously moving screens or the like, which comprises supporting a cylinder or bar of pulp between an upwardly moving 95 part of the screening surface and a stationary surface sloping toward the screening surface, said cylinder or bar of pulp being rotated by the movement of the screening surface the pulp on the screening surface adhering to the pulp cylinder and being thus removed from the screens.

4. The method of removing pulp from continuously moving screens or the like, which comprises supporting a cylinder or 105 bar of pulp between an upwardly moving

part of the screening surface and a stationary surface sloping toward the screening surface said cylinder or bar of pulp being rotated by the movement of the screening surface 5 face the pulp on the screening surface adhering to the pulp cylinder and being continuously scraped off the same by means of a stationary scraper.

In testimony that I claim the foregoing as my invention, I have signed my name in presence of two subscribing witnesses.

ANTON JULIUS SKJENNEBERG.

Witnesses:

C. NORMAN,
C. FABRICIUS HANSEN.
